UNITED STATES PATENT OFFICE.

JOSEPH DELANEY, OF ASHLAND, PENNSYLVANIA.

RATCHET AUGER-HANDLE.

SPECIFICATION forming part of Letters Patent No. 560,122, dated May 12, 1896.

Application filed December 28, 1895. Serial No. 573,604. (No model.)

To all whom it may concern:

Be it known that I, JOSEPH DELANEY, a citizen of the United States of America, residing at Ashland, in the county of Schuylkill and State of Pennsylvania, have invented certain new and useful Improvements in Ratchet Auger-Handles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide a ratchet auger-handle which is simple in construction, and in which the parts are held in engagement with each other by the means employed for attaching the auger to the handle.

20 With the above end in view the invention consists in providing the shank of the auger with a recess in which rest the sockets or parts of the ratchet mechanism to which the handles are connected, one of the handles

25 carrying a pawl having spring members adapted to engage a ratchet-wheel formed on one of the sockets, as will be hereinafter fully set forth, and particularly pointed out in the claims.

30 In the accompanying drawings, forming part of this specification, Figure 1 is a perspective view of my improved ratchet auger-handle. Fig. 2 is a vertical sectional view. Figs. 3 and 4 are detail perspective views of the sockets; and Fig. 5 is a plan view of the under side of the handle which carries the pawl, the socket having the ratchet-wheel being shown in dotted lines.

35 A designates a socket which is provided at one end with a cylindrical portion a and at the other end with a ratchet-wheel a' of larger diameter, the socket having centrally a longitudinal rectangular aperture or opening a^2 , through which the shank of the auger is passed, as well as the wedge which holds the parts together, as hereinafter described.

40 B designates a supplemental socket which is cylindrical and of slightly larger diameter than the cylindrical portion of the socket A, so that when these parts are placed end to end, as shown in Fig. 2, an annular recess will be presented, for the purpose hereinafter

set forth. The socket B is provided with a rectangular opening which registers with the opening a^2 in the socket A.

45 C designates a handle having attached thereto a shank c , at the outer end of which is formed a ring C' , which is preferably of greater thickness than the shank, and the opening in this ring is of the same diameter as the cylindrical portion a of the socket, so that when placed thereon the ring will bear upon the annular shoulder formed by the ratchet-wheel a' . To the under side of the shank c is pivoted a pawl D, having spring 60 members d , which are adapted to engage the teeth of the ratchet-wheel when the ring is placed upon the socket A, as hereinbefore mentioned. The shank c is provided with apertures c' , adjoining the spring members d 65 of the pawl, which are adapted to receive a pin d' , and when this pin is in engagement with one of the apertures it places one of the members of the pawl in engagement with the ratchet-wheel and throws the other member 70 out of such engagement.

75 E designates a handle which is provided with a shank e , having a ring at its outer end with an opening corresponding with the opening in the ring C' , so that this ring may be 80 placed over the cylindrical portion a of the socket A and rest upon the ring C' . The handle E and ring attached thereto are used for guiding the auger.

85 The shank F is tapered or beveled on one side toward its end, and the opposite side is provided with a recess of sufficient length to receive the sockets A and B, said recess forming shoulders f , against which the sockets bear. The part of the shank F that engages 90 the sockets is of less width than the openings therein, so that a wedge F' can be driven into the sockets to hold the parts firmly together.

95 In assembling the parts the socket A is placed over the end of the shank of the auger, so as to engage the lower shoulder f thereof. The rings of the handles C and E are then placed over the cylindrical portion of the socket and the supplemental socket placed over the end of the shank to engage the upper shoulder f , after which the wedge F' is 100 driven into the space between the shank and sides of the openings in the sockets and holds the parts securely together. It will be noted

that when the parts are assembled, as hereinbefore described, an annular recess is provided by the sockets A and B the rings of the handles C and E being held in said recess and allowed to turn therein, and by properly adjusting the pin d' either one of the spring members of the pawl D can be caused to engage the ratchet-wheel, thus providing for the turning of the auger in either direction.

10 The shank of the handle E is preferably given a double bend, as shown, so that the handles C and E can be brought substantially one above the other when desired.

From the foregoing description the operation of the device will be apparent.

Having thus described my invention, what I claim as new, and desire to secure by Letters Patent, is—

1. The combination with the shank of an auger having a recess, of the sockets A and B which receive the shank of the auger and provide an annular recess, one of the sockets carrying a ratchet-wheel; together with handles having rings which engage the annular recess; a pawl attached to one of the handles and in engagement with the ratchet-wheel; and means for rigidly connecting the auger to the sockets, substantially as shown and for the purpose set forth.

25 2. The combination with the sockets A and

B rigidly connected to the auger and providing an annular recess, substantially as shown, of the handles C and E having rings in engagement with the annular recess, a pawl D pivoted to one of the handles and presenting 35 spring members d d' , and a pin d' adapted to engage apertures c c' in the handle to throw either one of the spring members in engagement with a ratchet-wheel formed on one of the sockets, for the purpose set forth.

3. The combination with the shank of an auger beveled or tapered on one side and having a recess to provide shoulders, as f f' , of the sockets A and B presenting an annular recess and having central rectangular openings 45 which receive the shank of the auger, one of the sockets being provided with a ratchet-wheel, and a wedge or locking-key for holding the parts together, substantially as shown; together with a guide-handle and a handle carrying a pawl in engagement with the ratchet-wheel, the handles having rings in engagement with the annular recess formed by the sockets.

In testimony whereof I affix my signature 55 in presence of two witnesses.

JOSEPH DELANEY.
